CLAIM

The ornamental design for a drip tray for use with a mobile cleaning robot, as shown and described.

DESCRIPTION

FIG. 1 is a top, rear, right perspective view of a drip tray for use with a mobile cleaning robot, showing our new design, according to a first embodiment;

FIG. 2 is a top, front, left perspective view thereof;

FIG. 3 is a bottom, rear, right perspective view thereof;

FIG. 4 is a bottom, front, left perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The shade lines show surface contour and not surface ornamentation.

1 Claim, 8 Drawing Sheets
